DESIGN FOR A BARBECUE POT

James M. Huntington, La Canada, Calif.

Application July 1, 1935, Serial No. 57,481

Term of patent 14 years

To all whom it may concern:

Be it known that I, James M. Huntington, a citizen of the United States, residing at La Canada, county of Los Angeles, State of California, have invented a new, original, and ornamental Design for Barbecue Pots, of which the following is a specification, reference being had to the accompanying drawing, forming part thereof.

The figure is a perspective view of a barbecue pot, showing my new design the rear side of the barbecue pot being substantially like the front portion shown.

The dominant feature of my design resides in the inverted frusto-conical bowl having rows of perforations through its side wall and beneath which bowl is positioned an inverted conical member as shown.

I claim:

The ornamental design for a barbecue pot, as shown and described.

JAMES M. HUNTINGTON.
